Specification for Design.

Patented Aug. 2, 1921.

Application filed December 31, 1920. Serial No. 434,373. Term of patent 3½ years.

To all whom it may concern:

Be it known that I, FRANK S. HYATT, a citizen of the United States, residing at Brooklyn, in the county of Kings and State of New York, have invented a new, original, and ornamental Design for Cap for Powder-Container Tops, of which the following is a specification, reference being had to the accompanying drawings, forming part thereof, in which—

Figure 1 is a top plan view of a cap for powder container tops showing my design.

Fig. 2 is a side elevation of the same.

Fig. 3 is another side elevation of the same taken from a different position.

I claim:

The ornamental design for a cap for powder container tops, as shown.

FRANK S. HYATT.
